RAILWAY SIGNALING SYSTEM

Howard A. Thompson, Edgewood, Pa., assignor to
The Union Switch & Signal Company, Swiss-
vale, Pa., a corporation of Pennsylvania

Application March 25, 1941, Serial No. 385,039

1 Claim. (Cl. 246—130)

My invention relates to railway signaling systems and more particularly to systems of the type known as the continuous inductive track circuit type employing alternating current of a plurality of frequencies.

It is an object of my invention to provide a system of the type described and incorporating improved means for controlling crossing signals which protect the highway crossings in the track stretch in which the system is employed.

A further object of my invention is to provide a signal system of the type described employing energy of two frequencies to control the vehicle carried signal apparatus and employing energy of a third frequency to discontinue operation of a crossing signal.

Another object of my invention is to provide a signal system of the type described employing energy of a plurality of different frequencies to control vehicle carried signal apparatus and incorporating means for at times modifying the energy of one of these frequencies to provide means to control a crossing signal.

A further object of the invention is to provide a system of the type described and incorporating improved means for use at a cut section for supplying to the section in the rear of the cut section energy of the same frequency as is supplied to the section in advance of the cut.

Another object of my invention is to provide an improved railway signaling system.

Other objects of my invention and features of novelty will be apparent from the following description taken in connection with the accompanying drawings.

I shall describe two forms of railway signaling system provided by my invention, and shall then point out the novel features thereof in claims.

In the drawings Fig. 1 is a diagram of a railway signaling system embodying my invention, and

Fig. 2 is a diagram of a modified form of railway signaling system embodying my invention.

Similar reference characters refer to similar parts in each of the two views.

Referring to Fig. 1 of the drawings, there is shown therein a stretch of railroad track having track rails 1 and 2 over which traffic normally moves in the direction indicated by the arrow, that is from left to right.

The rails of the track stretch are divided by insulated joints 3 into the customary successive track sections. The portion of the track stretch shown in the drawings includes an intersection with a highway, and to provide for control of the crossing signals XS which protect the highway

intersection, the rails of the track section which includes the highway intersection are divided by insulated joints 3 into an approach subsection A12T and a clearing subsection B12T. The adjacent section in the rear is designated 11T, while the adjacent section in advance is designated 13T.

The system shown in the drawings is intended for use in track stretches without wayside signals, while the locomotives which are operated through the track stretch are equipped with cab signal apparatus arranged to respond to the alternating current energy supplied to the track rails of the various track sections. The system shown in the drawings is of the three indication variety and employs alternating currents of two different frequencies to provide two distinctive proceed indications, while the cab signal apparatus responds to the absence of energy in the track rails to provide the stop or most restrictive indication. In the system shown 60 cycle energy from a commercial source of current is employed to provide the clear indication, while 100 cycle energy supplied from such source by tuned alternators or equivalent devices is employed to provide the caution indication.

The cab signal apparatus is designed to distinguish between the two frequencies of alternating current. The construction of the cab signal equipment is not a part of this invention and any form of equipment well known in the art may be employed for this purpose. One form of equipment which may be used is shown in United States Patent No. 1,869,847, issued August 2, 1932, to Lars O. Grondahl.

The equipment is shown in the condition which it assumes when the track stretch is vacant. At this time 60 cycle alternating current energy is supplied to the rails of section 13T and feeds through a transformer 13RT and a rectifier 13R to the track relay 13TR so that the contacts of this relay are picked up. Contact 20, therefore, establishes a circuit to supply 60 cycle energy from line transformer 13TB to track transformer B12TT, while contact 21 interrupts the supply of energy to a tuned alternator 13TA and thereby maintains this device idle.

The 60 cycle energy supplied to the rails of section B12T feeds to the winding 23 of a device M which is similar in construction to a tuned alternator, but differs therefrom in that it is not tuned or adjusted to operate at a particular frequency, but is adapted to operate at either of two frequencies. The device M also differs from a tuned alternator in that the reed or mov-

ing element 25 does not control the circuit of the operating winding of the device.

On the supply of 60 cycle energy to the winding 23 of the device M the moving element 25 of the device is reciprocated between its two positions and establishes circuits to alternately energize the two portions of the primary winding of a track transformer A12TT at a rate such that 60 cycle energy is induced in the secondary winding of the transformer and is supplied therefrom to the rails of section A12T. The energy which is supplied to the track transformer is supplied from a line transformer B12TB through a rectifier RA.

In addition, when the reed or moving element 25 of the device M is in its right-hand position the winding of a control relay CR is energized in multiple with one portion of the primary winding of transformer A12TT, and contact 27 is picked up to interrupt the circuit of a code transmitter CT and to also interrupt a circuit including contact 240 of this device. Accordingly the code transmitter CT is maintained idle, and the device is constructed in such manner that its contact 240 is open at such times.

The 60 cycle energy supplied to the rails of approach section A12T feeds to transformers D and E which in turn supply current to relays A12TR and F. These transformers operate as described in United States Patent No. 1,704,110 to Clarence S. Snavely to distinguish between energy of different frequencies. These transformers are proportioned so that when 60 cycle energy is supplied thereto each supplies sufficient energy to its associated relay A12TR or F to maintain the contacts of such relay picked up.

As the contacts of relay A12TR are picked up contact 20 establishes a circuit to supply 60 cycle energy from a line transformer A12TB to a track transformer 11TT for section 11T, while contact 21 interrupts the circuit of an alternator A12TA.

As the contact 30 of relay F is picked up a circuit is established to supply energy from transformer A12TB through a rectifier RA to a crossing signal control relay XA, and contact 28 of this relay is picked up to interrupt the circuits of the crossing signals XS and thereby maintain these signals inactive.

When a train moving in the normal direction of traffic moves through the track stretch, the cab signal apparatus operates to provide the green or clear indication in each track section if energy of 60 cycle frequency is supplied to the rails of such section.

When a train enters section A12T, the relays A12TR and F release. Release of contact 30 of relay F interrupts the circuit of the relay XA and contact 28 of this relay releases and establishes the circuit of the crossing signals XS, and these signals operate to warn users of the highway way of the approach of a train.

In addition, on release of relay A12TR contact 20 interrupts the supply of 60 cycle energy from line transformer A12TB to the track transformer 11TT, and establishes a circuit from the alternator A12TA to the track transformer. As contact 21 of relay A12TR is released a circuit is established to supply energy from the rectifier RA to the alternator A12TA so that the alternator operates to supply energy of 100 cycle frequency to the track transformer 11TT.

Accordingly, if after the train under consideration vacates section 11T a second or following train enters section 11T, the cab signal equip-

ment carried thereby will receive energy of 100 cycle frequency and will provide its yellow or caution indication.

When the first train advances into section 5 B12T the device M is shunted and ceases to operate with the result that energy is no longer supplied thereby to the transformer A12TT or to the winding of relay CR. Contact 27 of relay CR, therefore, releases and establishes a circuit 10 to supply energy from a rectifier RA to the operating winding of the code transmitter CT, while contact 27 also establishes the circuit including contact 240 of code transmitter CT for supplying energy from the rectifier RA to the transformer A12TT.

The code transmitter CT, therefore, operates and when its contact 240 is closed energy is supplied from the rectifier RA to the right-hand portion of transformer A12TT, while the supply of energy to the transformer is interrupted when the contact 240 is open. The contact 240 is operated at a rate such as to provide 240 energy impulses a minute, so that alternating current of 4 cycle frequency is induced in the secondary winding of transformer A12TT and is supplied therefrom to the rails of section A12T.

When energy is supplied to the primary winding of transformer A12TT over the circuit controlled by contact 240 of code transmitter CT the rectifier K prevents the supply of energy to the relay CR so that this relay remains released and maintains the circuit of the code transmitter CT.

When the train vacates the approach section A12T, the 4 cycle energy supplied to the rails of this section feeds to the transformers D and E. The transformer D is of such size that too little energy is supplied through it to pick up the relay A12TR and this relay remains released so that energy of 100 cycle frequency continues to be supplied by alternator A12TA to section 11T. The transformer E is of such size, however, that sufficient energy is supplied to the relay F to pick up this relay so its contact 30 establishes the circuit of the relay XA, and contact 28 of this relay picks up to interrupt the circuit of the crossing signals XS and thereby discontinue operation of these signals.

If while the first train is present in the clearing section B12T a second or following train should enter the approach section, the relay F will become released and interrupt the circuit of relay XA to thereby again effect operation of the crossing signals. However, the cab signal equipment on this following train will not respond to the 4 cycle energy present in the rails of the approach section A12T at this time, and so this cab signal equipment will display its red or stop indication.

When the first train advances into section 60 13T, the track relay 13TR is shunted and its contacts 20 and 21 release to thereby cut off the supply of 60 cycle energy from line transformer 13TB to track transformer B12TT, and to cause the alternator 13TA to supply 100 cycle energy to the transformer B12TT. When section B12T is vacated this energy feeds to the winding 23 of device M and causes the reed or moving element 25 of this device to operate to alternately energize the two portions of the primary winding of transformer A12TT at a rate such that 100 cycle energy is supplied to the rails of section A12T, while energy is supplied to relay CR and its contact 27 picks up to interrupt the circuit of the code transmitter CT and of the contact 240 of

this device so that it ceases to supply energy to the transformer A12TT.

The 100 cycle energy supplied to the rails of section A12T feeds to the transformers D and E. Sufficient energy continues to be supplied through the transformer E to maintain the relay F picked up, while sufficient energy is now supplied through the transformer D to pick up the relay A12TR. When this relay picks up, the supply of 100 cycle energy to section 11T is discontinued and 60 cycle energy is supplied instead, while operation of the alternator A12TA is discontinued.

If, while a first train is present in section 13T, a second or following train should enter the approach section A12T the cab signal apparatus carried by the train would respond to the 100 cycle energy in the track rails to provide the yellow or caution indication, while the track relays A12TR and F would be released to effect operation of the crossing signals XS and to cause energy of 100 cycle frequency to be supplied to the rails of section 11T.

When the first train vacates section 13T, the track relay 13TR picks up and changes the energy supplied to section B12T from 100 cycle to 60 cycle, while the device M responds to this change in the energy supplied thereto to supply energy of 60 cycle frequency to section A12T.

Construction and operation of modification shown in Fig. 2

Referring now to Fig. 2 the equipment at the entrance end of section 13T is the same as the corresponding equipment in the system shown in Fig. 1, but the equipment shown in Fig. 2 employs different means to discontinue operation of the crossing signals when a train vacates the approach section.

The equipment is shown in the condition which it assumes when the track stretch is vacant. At this time energy of 60 cycle frequency is supplied to the rails of section 13T and track relay 13TR is picked up so that energy of this frequency is supplied to the rails of section B12T. This energy is supplied through the transformer B12RT and rectifier B12R to track relay B12TR, while this energy also is supplied to the operating winding 23 of device M which is similar to the corresponding device employed in the system shown in Fig. 1. Accordingly relay B12TR is picked up and its contact 30 establishes connection from the secondary winding of transformer ST to the primary winding of track transformer A12TT, while its contact 31 interrupts the circuit of the code transmitter CT.

As energy of 60 cycle frequency is supplied to the winding of device M the reed or moving element 25 of this device establishes and interrupts the circuit for supplying energy from the rectifier RA to the primary winding of transformer ST at a rate such that energy of 60 cycle frequency is induced in the secondary winding of this transformer and is supplied therefrom to the track transformer A12TT.

The 60 cycle energy supplied to the track rails of section A12T feeds through the transformer A12RT and rectifier A12R to the relays G and A12TR. As relay G is steadily picked up energy is not supplied through the decoding transformer A12DT to the relay H and the contacts of this relay are released.

As relay A12TR is steadily picked up its contact 32 establishes a circuit to supply energy from the rectifier RA to the relay XA and the

contact 28 of relay XA interrupts the circuit of the crossing signals XS to maintain these signals inactive.

In addition, contact 34 of relay A12TR interrupts the supply of energy to the alternator A12TA, while contact 35 establishes the circuit to supply energy of 60 cycle frequency from line transformer A12TB to track transformer 11TT so that energy of 60 cycle frequency is supplied to the rails of section 11T.

When a train moving in the normal direction of traffic, that is from left to right, enters section 11T the cab signal apparatus carried thereby responds to the 60 cycle energy to provide the green or clear indication. Similarly when the train advances into each successive section the cab signal apparatus responds to the 60 cycle energy to provide the green or clear indication.

When the train enters approach section A12T the track relays G and A12TR release. On release of contact 32 of relay A12TR the supply of energy to the relay XA is interrupted and contact 28 of this relay releases and establishes the circuit of the crossing signals XS so that these signals operate to warn users of the highway of the approach of a train.

On release of relay A12TR contact 35 interrupts the supply of 60 cycle energy from line transformer A12TB to the track transformer 11TT, and establishes a circuit to permit 100 cycle energy from the alternator A12TA to be supplied to the track transformer, while contact 34 establishes a circuit to supply energy from the rectifier RA to the alternator A12TA so that the alternator operates and 100 cycle energy is supplied to the rails of section 11T.

On release of the contacts of relay G an impulse of energy is supplied through the decoding transformer A12DT to the relay H, but the relay H is somewhat slow to pick up and does not become picked up on the supply of one impulse of energy thereto. Accordingly contact 37 of this relay remains released and does not establish a circuit to supply energy to the relay XA.

When the train advances into the clearing section B12T the track relay B12TR and the winding 23 of device M are shunted so that relay B12TR releases and device M ceases to operate. Release of contact 30 of relay B12TR establishes the circuit of code transmitter contact 75, while release of contact 31 of relay B12TR establishes a circuit to supply energy from the rectifier RA to the winding of code transmitter CT. The code transmitter CT has a contact 75, which when the device is energized is operated between its released and picked-up positions at a suitable rate, such as 75 times a minute, so as to provide 75 energy impulses per minute which are separated by periods of equal duration during which no energy is supplied. Accordingly, the contact 75 of the code transmitter is operated and establishes a circuit to supply impulses of 60 cycle energy from the line transformer B12TB to the transformer A12TT and thus to the rails of section A12T. The circuit for supplying energy to the transformer A12TT is traced from one terminal of the secondary winding of line transformer B12TB through code transmitter contact 75, back contact 30 of relay B12TR, and primary winding of transformer A12TT to the other terminal of the secondary winding of line transformer B12TB.

When the train vacates the approach section A12T the impulses of energy supplied through transformer A12TT feed to the relays G and

A12TR and cause alternate picking up and releasing of the contacts of these relays.

As a result of this code following operation of the contacts of relay G energy is supplied through the decoding transformer A12DT to the relay H, and contact 37 of relay H picks up and establishes a circuit to supply energy from the rectifier RA to the relay XA so that contact 28 picks up and interrupts the circuit of the crossing signals XS which thereupon cease to operate.

In addition, at this time, contact 38 of relay H picks up and establishes a circuit shunting the winding of relay A12TR so that this relay no longer responds to the coded energy. Instead its contacts remain released and maintain the supply of 100 cycle energy from the alternator A12TA to the transformer 11TT.

The relay H is of a type which is slow in releasing so that its contacts remain picked up during the intervals between the supply of impulses of energy thereto from the decoding transformer A12DT.

If, while clearing section B12T is occupied, a second or following train advances into section 11T the cab signal apparatus carried thereby will respond to the 100 cycle energy in the track rails to provide the yellow or caution indication. When the second or following train advances into the approach section A12T the cab signal apparatus will respond to the coded 60 cycle energy in the section rails to alternately flash the green or clear lamp and the red or stop lamp. The flashing indication will be regarded as a block occupied signal by the operating rules for this track stretch.

If a train enters the approach section A12T at a time when the clearing section B12T is occupied, at which time coded energy is supplied to the rails of section A12T, the track relay G will be shunted and will cease to follow code. This will cut off the supply of energy through the decoding transformer A12DT to the relay H and the contact 37 of the relay D will release and interrupt the supply of energy to the relay XA so that contact 28 of this relay releases and initiates operation of the crossing signals to warn users of the highway of the approach of a train.

When the first train advances into section 13T track relay 13TR is shunted and energy of 100 cycle frequency is supplied to the rails of section B12T, and when the train vacates the clearing section, this energy feeds to the track relay B12TR and to the operating winding 23 of device M. Accordingly contact 39 of relay B12TR picks up to interrupt the supply of coded 60 cycle energy to section A12T, while contact 31 interrupts the supply of energy to the code transmitter CT. In addition, device M operates to establish and interrupt the circuit of the primary winding of transformer ST at a rate such that energy of 100 cycle frequency is induced in the secondary winding of this transformer, and this energy is supplied to track transformer A12TT over the circuit including front contact 30 of track relay B12TR.

On the supply of steady 100 cycle energy to the track relay G its contacts remain picked up and energy is no longer supplied through the decoding transformer A12DT to the relay H and the contacts of this relay become released. On release of contact 38 of this relay the circuit shunting the winding of relay A12TR is interrupted and thereupon the contacts of this relay pick up.

On release of contact 37 of relay H the supply

of energy to the relay XA is interrupted, but the supply of energy to this relay is reestablished on picking up of contact 32 of relay A12TR, and the relay XA is of a type which is slow in releasing so that its contact 28 remains picked up during this momentary interruption in the supply of energy to the relay winding. Accordingly the crossing signals XA remain inactive at this time.

In addition, on picking up of the contacts of relay A12TR operation of the alternator A12TA is discontinued, while the circuit for supplying 60 cycle energy from the line transformer A12TB to the track transformer 11TT is established.

Accordingly, if while section 13T is occupied a second or following train enters either the approach section A12T or the clearing section B12T the cab signal apparatus on the train will operate to provide the caution indication, while track relay A12TR will release and its contact 32 will interrupt the supply of energy to the relay XA so that this relay releases and initiates operation of the crossing signals.

When the first train vacates section 13T the track relay 13TR picks up and the energy supplied to section B12T is changed from 100 cycle frequency to 60 cycle frequency, while there is a similar change in the energy supplied to section A12T.

From the foregoing it will be seen that I have provided a signaling system which employs a minimum of apparatus to produce two distinctive proceed indications.

In addition, it will be seen that apparatus embodying my invention provides for a special form of energy in the approach section to a highway crossing to discontinue operation of the crossing signals without producing a proceed cab signal or changing the energy supplied to the adjacent section in the rear.

It will be seen also that in each modification of the invention alternating current energy of one frequency supplied from a commercial source of energy is employed to provide the clear indication, while energy of a different frequency supplied from such source by alternators is employed to provide the caution indication. The alternators are so controlled as to operate only when current is required from them, and as this is only a small part of the time, the life of the alternators is prolonged to the maximum.

In addition, it will be seen that each modification incorporates means at the cut section for relaying or repeating to the rails of the section in the rear of the cut energy of the same frequency as is supplied to the rails of the section in advance of the cut.

Although I have herein illustrated and described only two forms of railway signaling system embodying my invention, it is understood that various changes and modifications may be made therein within the scope of the appended claim without departing from the spirit and scope of my invention.

Having thus described my invention, what I claim is:

In combination, a stretch of railway track intersected by a highway and comprising a signal approach section and a signal clearing section, a crossing signal for the intersection, means governed by traffic conditions in advance of said clearing section for supplying to the rails of said clearing section train governing energy comprising continuous alternating current of a first or a second frequency, a track transformer having its secondary winding connected across the rails

of said approach section, a source of unidirectional current, a control relay, an electroresponsive device having a winding receiving energy over the rails of said clearing section and having a member operated at a rate determined by the frequency of the energy supplied to the winding of said device, said member controlling circuits for supplying energy from said source of unidirectional current to the primary winding of said track transformer and to said control relay, a coding device having a contact effective when the device is energized to periodically establish a circuit to supply energy from said source of unidirectional current to said track transformer primary, the rate of operation of said coding device contact being such that the frequency of the energy induced in the track transformer secondary winding when current is supplied to the transformer primary winding over the circuit controlled by said coding device is substantially

lower than that of the train governing energy, said control relay being effective when released to establish a circuit to supply energy to said coding device, a first track relay receiving energy over the rails of said approach section through a first transformer and a second track relay receiving energy over the rails of said approach section through a second transformer, the first relay and transformer being proportioned so that said relay is picked up when and only when energy of the train governing frequencies is supplied to said transformer, the second relay and transformer being proportioned so that the relay is picked up when energy of either train governing frequency or said lower frequency is supplied to said transformer, said first relay controlling the supply of train governing energy to the rails of the adjacent section in the rear, said second relay controlling said crossing signal.

20

HOWARD A. THOMPSON.
